HARTWELL W. WEBB, OF CRESSKILL, NEW JERSEY.

METHOD FOR RECORDING SOUND.

Application filed June 19, 1919. Serial No. 305,432.

To all whom it may concern:

Be it known that I, HARTWELL W. WEBB, a citizen of the United States, residing at Cresskill, in the county of Bergen and State 5 of New Jersey, have invented certain new and useful Improvements in Methods for Recording Sound, of which the following is a specification.

This invention relates generally to sound 10 recording and particularly relates to a new and improved method for producing sound records through photographic agencies.

As is well known, the existing methods for producing sound records usually include as 15 one step in the operation the use of a cutting tool which cuts a groove in a moving wax or similar surface, the groove having either vertical or horizontal variations transverse its length that are produced by a mechanical 20 connection of the cutting tool with a diaphragm that is adapted to be vibrated by sound waves representing the sounds desired to be reproduced. From the sound record thus obtained, a master cameo record 25 is made from which a multiplicity of sound records in a permanent form are produced by well-known processes. Although records made by the general methods referred to have gone into wide and extensive use, it is 30 in spite of the fact that, with a mechanical cutting tool it is impossible to faithfully represent the recorded sounds or tones with any close approach to their original purity or richness, not only because the weight and 35 resulting inertia and momentum of the cutting member, through its physical and mechanical connection with the diaphragm, acts to damp the free vibration of the diaphragm in response to the action of the 40 sound waves directed throughout, but also because of the resistance offered by the wax or equivalent material to the movement of the cutting tool therein.

It has long been recognized that, if an 45 imponderable element, such as a ray of light, could be substituted for the cutting tool, the serious objections attending the use of the cutting tool would be eliminated, and a very considerable step forward in 50 the art of sound reproduction would have been achieved, provided, of course, that proper advantage had been taken of the situation and a suitable relief record evolved for use in subsequent reproduction of the 55 recorded sounds. Many attempts have accordingly been made to utilize photographic

methods for producing a sound record in black and white and of forming from the photographic record by photo-engraving processes a record in relief by means of 60 which the sounds originally recorded could be reproduced. However, so far as I am aware, none of such attempts has been successfully developed to a point where the method chosen has gone into practical and 65 commercial use. The reason for this has been due to a complete failure on the part of the experimenters to appreciate the necessity for employing a recording light of 70 a character and in a manner suited to the requirements of the work, that is, in such a way that a sufficiently intense exposure could be made on the rapidly moving sensitive surface, to affect the surface to the required degree, and which would be free 75 to act unhampered by diffraction effects so as to produce a path of exposure having sharply defined lateral edges.

In the course of experiments conducted 80 for the purposes of the invention, I have discovered that a sufficient exposure for the purpose can be obtained by the use of a very intense source of artificial light placed comparatively near the sensitive surface 85 which is to receive the record. In order 90 to obtain the sharp and well-defined lateral light-path margins that are essential for the purpose, it is necessary that the source of light to be relatively minute, so that, coupled with the near relation to the sensitized surface in which it is placed, a condition can be secured by which with the aid 95 of suitable stop means a powerful beam of parallel rays can be obtained which, by means of a suitable sound-wave controlled orifice, can be projected against the record-receiving surface undispersed and undeviated by diffraction effects.

I have found that the character and unvarying intensity of light emitted from a 100 short section of tungsten filament is well adapted for the purpose in view and that, because of the small compass in which a source of light of this type can be provided, it can be favorably utilized by mounting the 105 light source comparatively near the record-receiving surface, and preferably directly on the sound box framework of the reproducing machine or on the recording arm itself. Preferably the section of filament 110 used is somewhat elongated in comparison to its width, and the length of the section

is parallel to the sensitive surface and substantially in the direction of movement of the record-receiving surface, so as to produce a longitudinal overrunning or overlapping of the projected beam in order to produce an increased exposure along the path of the beam on the surface.

I have also found that the contour of the sound-wave representing channel or ridge 10 eventually obtained can be determined in advance by correspondingly regulating the cross-sectional area of the recording light beam so as to increase the intensity of the light along the center of the traced path, 15 and that I can in this way produce a photographic effect that will automatically produce an approximately V or semi-elliptical groove section which is better adapted for the purpose than would be a rectangular or 20 approximately rectangular section.

From the photographic record made by the use of the apparatus referred to a negative is developed in which the recorded sounds are represented by an undulating 25 opaque spiral line. From this record a positive is printed and developed in a well-known manner and, by a preferred method, I expose a film of gelatine sensitized with ammonium dichromate to light passing 30 through the positive plate and develop the dichromated gelatine to produce a record in relief from which a master record, suitable for use in the production of commercial reproducing records, can be produced.

35 In the drawings.—

Figure 1 is a side elevation of a portion of a photographic recording apparatus embodying the form of a part of my invention;

40 Figure 2 is a plan view, partly broken away, of the device shown in Figure 1;

Figure 3 is an enlarged sectional view showing a preferred form of light-projecting means employed in the initial recording 45 step;

Figure 4 shows on an enlarged scale a variety of forms of orifice that may be employed in the light-controlling shutter;

50 Figure 5 shows on an enlarged scale the relation that exists between the section of filament serving as a light source and the relative direction of movement of the shutter and the plate;

Figure 6 shows a side elevation of a modified form of mounting for the recording lamp; and

Figure 7 is an end view, partly in section and partly in elevation, of the device shown in Figure 6.

60 I have illustrated in the drawings at 1 in Figure 1 the turntable of a recording machine on which may be placed a plate or film 2 having a light-sensitized upper surface. The turntable and the sensitized plate carried thereby are adapted to be rotated

about a vertical axis so that a sound box 3 associated therewith, when given a movement along a radius drawn from the axis of rotation of the plate, will trace a spiral path in a manner well exemplified in talk- 70 ing machine records of the disc type.

In order to produce in the sensitized surface of the plate a light tracing that will represent the movements of the diaphragm 4 of the sound box 3 in response to the sound waves acting thereon, a source of light preferably taking the form of an electric incandescent lamp 5, is mounted in a tubular support 6 attached to a bracket 7 carried directly by the sound box 3, as shown in 80 Figures 1 and 2. In order to control the action of light on the plate in accordance with the movements of the diaphragm, I employ a shutter, preferably taking the form of a disk 9 carried at the end of a 85 lever 10 between the lower end of the lamp 5 and the plate 2. The lever 10 is preferably pivoted at 11 on the margin of the sound box 3 and connected intermediate its ends to the diaphragm, so that the vibrations of the diaphragm are transmitted to the shutter which is reciprocated in a path transverse to the length of the section of filament 8 to thereby produce in the light-traced path lateral undulations correspond- 90 ing to the movements of the diaphragm.

I provide for securing an adequate intensity of light for the purpose by making use of a tungsten filament 8 because of the high actinic value and intense and unvarying character of the light given off by an incandescent filament of this type, and also by mounting the lamp in such a position that the filament is placed at a distance of approximately one-half of an inch from the sensitized surface of the plate 2. I still further add to the effectiveness of the illumination furnished by the light by making use of the comparatively elongated section of filament 8 the width of which is approxi- 105 mately the same as or very little in excess of the groove in the finished record or between .003 and .006 of an inch and whose active length is about double its width, which 110 I place in a parallel position with relation to the plate 2 and with its length lying in the direction of movement of the plate. By means of suitable light-controlling means 115 hereinafter referred to, I provide that the cross-section of the light beam reaching the plate has the general formation of the sector of filament comprising the light source, and by reason of the fact that the elongated light spot lies with its length in the direction of travel of the plate, an overrunning or over- 120lapping of the light spot along the path of the beam is secured, which has the effect of increasing the length of exposure of the sensitized surface of the light along the path of travel.

125 130

Reference has already been made to the importance of producing a light-traced path having sharp and clean-cut lateral edges, and it will be seen that by reason of the location of the source of light in the immediate vicinity of the sensitized surface, I am able to obtain a beam of rays that is diverted to a minimum degree by the effects of diffraction. In order to still further insure that a beam of parallel rays is provided, I preferably make use of a light-directing aperture 12 of relatively substantial length in comparison with its width and having a uniform cross-section from end to end. The use of this construction has the effect of passing the beam of light through two separated and spaced apart aligned openings of equal size and thus procuring a beam of rays that are substantially parallel, so that a short beam of uniform section is obtained between the exit end of the aperture and the surface of the plate in which the diaphragm-controlled orifice is placed in such close adjacency to the surface of the plate that the effects of diffraction on the light beam reaching the plate through the orifice are, for all practical purposes, completely nullified.

I preferably provide for producing a greater illumination in the center of the line than at the lateral margins in such progressively-increasing proportions as to determine the securing of a V-shaped or semi-elliptical groove section in the reproducing records finally obtained. I procure this desirable result by means of the particular conformation of the cross-sectional area of the recording light beam, an illustration of which is shown in Figure 4 of the drawing in which A presents an elliptical orifice, B and D triangular, and C a diamond-shaped opening. The beam of light passing through the orifices A, C and D will produce a path of exposure in which the central zone is more intensely illuminated than the marginal portions, as will be clear. With the orifice shown at B, a record tracing is secured which gradually changes the intensity of exposure from one side to the other of the record path to produce a final groove having one side perpendicular to the surface of the plate to compensate for the lateral pressure of the groove against the stylus of the reproducing machine. In order to produce the overrunning of the spot of light along the path of the beam in the manner already referred to, the elongated orifices shown in Figure 4 are arranged with their lengths lying in the direction of travel of the plate 2, as is indicated in Figure 5, while the movement of the shutter 9 and the orifice is transverse the longer axis of the orifice, as is also indicated in this figure.

While the structural arrangement of re-

cording lamp and shutter already described is a preferred one, I may, in an alternative construction, mount the light source upon an operating lever 15 between the diaphragm center and the orifice 12 so that the orifice, instead of traversing the path of the beam, moves bodily with it. In this case the source of light is preferably mounted at the pivotal point of the operating bar or lever 15 in order that it may interfere as little as possible with the action of the diaphragm. In either construction, whether the orifice is carried by the lamp casing or contained in a separate shutter, the size of the orifice and the distance by which it is spaced from the surface of the plate 2 is extremely small so that a sharply defined path of exposure sufficiently fine and narrow for the purpose, is obtained. In actual practice I have found that an orifice .005 of an inch in width and placed one-thirtieth of an inch from the plate has given satisfactory results.

The record which I produce by means of the apparatus described is preferably formed on plates or films of fine grain in order to insure in a still greater degree the sharpness of the lateral margins, and I develop the negative records thus formed in such a way as to secure a high degree of contrast. I preferably preserve the negative record as a master and use it in the production of positive records in black and white from which relief records are produced, although the negative record may be used directly in the production of records in relief. By my preferred method I copy the negative in black and white by photographic means upon a plate or film and obtain a positive in which the original light tracing representing the vibrations of the diaphragm is represented in the form of a clear or white sinuous line which is intensely clear at the center but gradually becomes dark or opaque toward the lateral margins. I may increase the darkening effect toward the margins to any desired extent and without affecting the sharpness of the margins which was definitely established in the negative, by exposing in diffused light so that light falls behind the dark tracing on the negative to the desired degree.

In order to obtain a relief record from the positive record in black and white obtained by the printing process last referred to, I attach to the film side of the positive plate a gelatine plate having a thickness equal at least to the depth of the finished relief I desire to obtain. I then place the positive with the attached gelatine plate in a bath of cold water to which a small quantity of glycerine has been added for the purpose of facilitating the manipulation of the gelatine. When the first swelling of

the gelatine has occurred, I squeegee the elongated orifice elongated in the direction of relative travel and placed in such close relation to the surface that substantially no diffraction of the light occurs, said orifice being affected by the movements of said sound-actuated member to control said light. 45

5 the gelatine to the positive, sensitize with ammonium dichromate and dry the gelatine in a manner well known in the photographic art. I then expose the positive with the sensitized gelatine attached thereto to light passing through the positive plate from the back thereof in order that the diachromated material which is rendered non-soluble by 10 the light may lie against and adjacent the plate supported side of the gelatine so as to insure the firm attachment of the insoluble matter to the plate.

15 After exposure, I develop the gelatine plate in hot water in a manner well-known in the art and thus secure a relief record which is the reverse of the final record in that the tracing is in raised or cameo form. An impression of this relief record may be 20 made in soft lead or other material in a hydraulic press or by a molding process. From this impression as a basis the operation of producing records suitable for use in sound-reproducing machines may take 25 place in the usual manner.

What I claim is:

1. The method of making a sound record, which consists in photographically recording on a relatively movable sensitized surface 30 the movements of a sound-actuated member by means of a beam of parallel light rays projected from a relatively small elongated source of light placed parallel to and with its length lying in the direction 35 of movement of the relatively movable sensitized surface.

2. The method of making a sound record, which consists in photographically recording on a relatively moving sensitized surface 40 the movements of a sound-actuated member by means of light projected from a source through an adjacent transversely

50 record, which consists in photographically recording in the form of an opaque line in a bromide-sensitized surface the movements of a sound-actuated member by means of light projected from an adjacent source 55 and through an orifice placed in such close relation to the surface that substantially no diffraction occurs, in employing the negative thus produced to form a positive record in which the movements of the sound-actuated member are recorded in the form 60 of a transparent line, in applying gelatine to the positive record thus formed, in sensitizing the gelatine with dichromate, in exposing the dichromate-sensitized gelatine to light passing through the positive record, and in treating the dichromate-sensitized gelatine to produce a record in which the movements of the sound-actuated member are manifested in the form of an elevated 65 ridge.

4. The method of making a sound record, which consists in photographically recording on a sensitized surface the movements of a sound-actuated member by means of a transversely elongated beam of parallel light rays controlled by the movements of said sound-actuated member, the cross-sectional area of said beam having a conformation such as to increase the intensity of 75 light at the central portion of the path of exposure. 80

HARTWELL W. WEBB.
